UNITED STATES PATENT OFFICE.

GOTTLIEB W. DAIMLER, OF DEUTZ-ON-RHINE, GERMANY.

IMPROVEMENT IN GAS-MOTOR ENGINES.

Specification forming part of Letters Patent No. 222,467, dated December 9, 1879; application filed October 27, 1879; patented in England, August 12, 1879.

To all whom it may concern:

Be it known that I, GOTTLIEB WILHELM DAIMLER, of Deutz-on-Rhine, in the German Empire, have invented an Improvement in Gas-Motor Engines; and I do hereby declare that the following description, taken in connection with the accompanying drawings hereinafter referred to, forms a full and exact specification of the same, wherein I have set forth the nature and principles of my said improvement, by which my invention may be distinguished from others of a similar class, together with such parts as I claim and desire to secure by Letters Patent—that is to say:

This invention has reference to that description of gas-motor engines in which every alternate stroke of the piston constitutes the working-stroke; and it consists mainly in combining the cylinders of two such engines in such manner with a third cylinder that the gaseous products of combustion under pressure, after acting in the first-named cylinders, pass thence into the last-named cylinder, in order, by their expansion therein, to perform a further amount of work, which is transmitted to the same engine-shaft to which the pistons of the high-pressure cylinders are connected.

By this means an increased useful effect is obtained from the combustible gases employed as motive power, and a more uniform motion of the engine is attained.

The construction of a compound engine operating according to this invention is shown on the accompanying drawings, in which—

Figure 1 shows a side elevation of the engine, partly in section, and with one of the high-pressure cylinders removed. Fig. 2 shows a sectional plan. Fig. 3 shows a back-end elevation; and Fig. 4 shows a cross-section on line $\alpha\alpha$ of Fig. 2.

The two high-pressure cylinders $A' A^2$ are

open to the atmosphere at the front end, and contain pistons $B' B^2$, which by one outstroke draw in a charge of combustible gas and air, which is compressed by the following instroke, the charge being then fired, causing the piston to perform its working outstroke, and by the next instroke the gaseous products of combustion are expelled, the mode of operating being so far the same as described in the specification to Otto's United States Patent of 14th August, 1877.

The two pistons $B' B^2$ are so connected by their piston-rods to cranks $C' C^2$ on the engine-shaft C as to perform their outstrokes simultaneously, or nearly so, but these strokes are so timed that while the one piston is performing the stroke by which the combustible charge is drawn into the cylinder, the engine-shaft is propelled by a working-stroke at every revolution, instead of only at every other revolution, as would be the case with a single working-cylinder. In like manner, while the one piston is performing its compressing instroke, the other performs its expelling instroke.

Instead of allowing the expelled gases to escape into the atmosphere, as was the case in the engine described in the above-mentioned patent, they are caused to enter a third cylinder, A^3 , whose piston B^3 they consequently propel outward by their expansive force, and such piston being connected by its rod to a crank, C^3 , on the engine-shaft opposite those $C' C^2$ of the high-pressure cylinders, or nearly so, it will be seen that the piston B^3 will perform its outstrokes (each of which is a working-stroke) simultaneously with the instrokes of the pistons $B' B^2$. Hence during two revolutions of the engine-shaft the following functions will be performed consecutively by the three cylinders:

Half-revolution of crank-shaft.	High-pressure piston I.	Low-pressure piston III.	High-pressure piston II.
First	Makes outstroke, drawing in charge.		Makes outstroke, being propelled and doing work.
Second	Makes instroke, compressing charge.	Makes outstroke, worked by expansion of exhaust from II.	Makes instroke, expelling exhaust into III.
Third	Makes outstroke, being propelled and doing work.	Makes instroke, expelling exhaust.	Makes outstroke, drawing in charge.
Fourth	Makes instroke, expelling exhaust into III.	Makes outstroke, being worked by expansion of exhaust from I.	Makes instroke, compressing charge.

This cycle of operations is continuously repeated.

From the above it follows that with this arrangement there will occur during each revolution of the shaft two impulses, the one being from one of the high-pressure cylinders, and the other from the low-pressure cylinder. The passage of the gaseous products from the high-pressure cylinders to the low-pressure cylinders can commence before the pistons of the former arrive at the extreme end of out-stroke; but the low-pressure piston must at that time have just arrived at the extreme end of its instroke.

The communications between the high and low pressure cylinders for effecting the above-described operations are governed by means of valves $D' D^2$ in communicating passages $E' E^2$, and the escape of the products from the low-pressure cylinder is regulated by the valve F , closing an escape-passage, F' . In order to prevent the gases under pressure that are passing from the one high-pressure cylinder to the low-pressure cylinder from passing also to the other high-pressure cylinder, (which at that time will just be commencing its compressing-stroke, and will consequently contain gases at low pressure,) check-valves $G' G^2$ are provided.

In order to equalize the pressure on each side of the valves $D' D^2$, so as both to prevent loss of useful effect and wear and noise in working, the pressure in the communicating passages $E' E^2$ is maintained approximately equal to that of the gases passing from the high to the low pressure cylinders by causing the escape-valve F to the latter to close before its piston arrives at end instroke, so as to produce back pressure; and to enable such back pressure to pass to the under side of the valves D' or D^2 before this is opened, the check-valve G' or G^2 is opened slightly in advance thereof and simultaneously with the closing of the escape-valve F . The opening of the valves $D' D^2$ and $G' G^2$ is effected from a counter-shaft, H , by means of a crank, I , and connecting-rod I' , working a lever, I^2 , on a rocking shaft, J , carrying the rocking arms $J' J^2$, with tappets, which act on the lower ends of the valve-stems, so as to press these upward against the action of springs, as shown. The crank I also imparts the requisite reciprocating motion to the usual admission and ignition slides $K' K^2$ of the high-pressure cylinders by means of the connecting-rod K^3 . The escape-valve F of the low-pressure cylinder is actuated by two cams or tappets, $L' L^2$, on the counter-shaft H through the bell-crank levers M . In order to reduce the work of compression during the first compressing-strokes of the high-pressure cylinders on first starting the engine, these are provided with escape-valves $N' N^2$, that are kept open during the first part of such strokes by means of tappet-levers $O' O^2$, actuated from the levers $J' J^2$, so as to allow a portion of the first charge of the cylinders to escape. The levers $O' O^2$ are capable of being slid upon their pins, so as to be

thrown out of gear with the levers $J' J^2$ after the engine is started, as indicated by the dotted positions $O^3 O^4$ at Fig. 2.

In like manner the escape-valve F of cylinder A^3 is kept open during the first outstroke of the piston, in order to prevent a vacuum being formed behind it, this being effected by means of a sliding pin, T , as shown at Fig. 1, such pin being drawn backward, as indicated by the dotted lines, when the engine is started.

The supply of combustible gas to the slides $K' K^2$ of the high-pressure cylinders is regulated by means of the gas-valve P , actuated by a bell-crank lever, P' , from a sliding cam, P^2 , on the counter-shaft H , controlled by a governor, Q , in a similar manner to that described in the before-mentioned patent of Otto, the valve being opened twice in one revolution of the shaft.

The gas passes from the valve P through the pipes $R R'$ to the engine-slides, which are also constructed and operate in a similar manner to that described in Otto's patent. They are so timed in their working that while the gas is passing into the slide of the one cylinder it is cut off from the slide of the other cylinder.

The counter-shaft H receives its motion from the engine-shaft C through gearing $S S'$, so as to make one revolution for every two revolutions of the engine-shaft. The cylinders and passages are inclosed by jackets cooled by water circulation.

The above-described engine may also be constructed without the low-pressure cylinder, in which case the two high-pressure cylinders discharge their products of combustion into the atmosphere, working otherwise the same as above described. Also, a single high-pressure cylinder may be combined with the low-pressure cylinder, operating in the same manner as above described.

Having thus described the nature of my invention, and in what manner the same is to be performed, I claim—

1. A gas-motor engine having two parallel and disconnected high-pressure cylinders, each of which consecutively draws in a combustible charge, compresses it, fires it, and performs the working-stroke, and expels the products of combustion, the two disconnected and independent pistons of the two cylinders being connected to one and the same engine-shaft, so as to perform their strokes together, but the working-stroke of the one cylinder being made to take place while the other cylinder is drawing in its combustible charge, substantially as described.

2. In a gas-motor engine, the combination of two high-pressure cylinders, each of which consecutively draws in a combustible charge, compresses it, fires it, and performs the working-stroke, with a low-pressure cylinder into which the gaseous products are caused to pass alternately from the high-pressure cylinders, so as to perform further work by expansion therein, substantially as herein described.

3. In a gas-motor engine, the combination of

two high-pressure cylinders whose alternate outstrokes are working-strokes, with a low-pressure cylinder into which the products of combustion pass from the high-pressure cylinders, the one high-pressure piston being made to perform its working-outstrokes simultaneously with the charging-outstrokes of the other, while the low-pressure piston performs a working-outstroke during each instroke of the high-pressure cylinders, substantially as herein set forth.

4. In a gas-motor engine wherein two high-pressure cylinders operate in combination with one low-pressure cylinder in which the products of combustion from the high-pressure cylinders are caused to actexpansively, a shaft revolving at half the speed of the engine-shaft and operating the two admission-slides of the high-pressure cylinders and the admission and check valves from the high-pressure cylinders to the low-pressure cylinder by one and the same crank or eccentric, the discharge-valve to the low-pressure cylinder being operated by separate cams or tappets on the said shaft, substantially as herein described.

5. In a gas-motor engine, the combination of the high-pressure cylinders A' A² with low-

pressure cylinder A³, communicating-passages E' E², admission and check valves D' D² G' G², actuated by crank I and tappet-levers J' J², and escape-valve F, actuated by cams N and lever M, operating substantially as herein set forth.

6. In gas-motor engines, the combination, with the high-pressure cylinders A' A², of escape-valves N' N², operated by tappet-levers O' O², capable of being slid in and out of action with levers J' J², operating the admission-valves, substantially as and for the purposes herein set forth.

7. In combination with the escape-valve F of the low-pressure cylinder, the pin T, capable of being slid so as to keep the valve F open, substantially as and for the purposes set forth.

In testimony whereof I have signed my name to this specification in the presence of two subscribing witnesses this 4th day of September, A. D. 1879.

GOTTLIEB WILH. DAIMLER.
